BUNDLING STRAP

William P. Miller, Elizabeth, N.J., assignor to The Thomas & Betts Co., Elizabeth, N.J., a corporation of New Jersey

Filed Apr. 4, 1966, Ser. No. 1,749

Term of patent 14 years

(Cl. D17—5)

Portions of the design are shown broken away in FIGS. 1 and 2 to indicate indefinite length.

This application is a continuation in part of my application Serial Number D-85,052, filed May 3, 1965, now abandoned.

I claim:

The ornamental design for a bundling strap, as shown and described.
